G. C. DAVISON ET AL

FIXED AMMUNITION FOR LINE THROWING GUNS

Original Filed May 14, 1919

UNITED STATES PATENT OFFICE.

GREGORY C. DAVISON AND CECIL P. CAULKINS, OF NEW LONDON, CONNECTICUT, AS-SIGNORS, BY MESNE ASSIGNMENTS, TO AMERICAN ORDNANCE CORPORATION, OF NEW YORK, N. Y., A CORPORATION OF DELAWARE.

FIXED AMMUNITION FOR LINE-THROWING GUNS.

Application filed May 14, 1919, Serial No. 297,130. Renewed May 26, 1923.

To all whom it may concern:

Be it known that we, GREGORY C. DAVISON and CECIL P. CAULKINS, citizens of the United States, both residing at New London, 5 in the county of New London and State of Connecticut, have invented certain new and useful Improvements in Fixed Ammunition for Line-Throwing Guns; and we do hereby declare the following to be a full, clear, and 10 exact description of the invention, such as will enable others skilled in the art to which it appertains to make and use the same.

Our invention relates to improvements in fixed ammunition for use with line throwing 15 guns, which guns are used to throw lines from a stranded vessel to the shore, or from the shore to a stranded vessel, or from one vessel to another, for lifesaving, salvage or other purposes.

20 The object of our invention is to provide a simple and convenient form of fixed ammunition, or projectile, on which the line to be carried may be attached, and which fixed ammunition may be loaded as a unit into the 25 gun and fired therefrom as will be herein-after described.

Our invention is intended more especially for use with the apparatus described in our 30 application filed of even date herewith, serially numbered 297,129 and entitled Improvements in line throwing guns.

Our invention will be more fully understood after reference to the accompanying drawings, in which like parts are indicated 35 by similar reference symbols throughout the several views, and in which:—

Figure 1 is a side elevation of the complete fixed ammunition, the line attached thereto being shown in dotted lines.

40 Figure 2 is a sectional elevation of the base of the projectile and of the cartridge case shown in Figure 1, the parts being shown on a larger scale than in said figure, and

45 Figure 3 is a rear view of the device shown in Figure 2.

1 represents the projectile which is preferably made of cast metal, such as cast iron, and is curved as at 2, and reduced as at 3, 50 terminating at its forward end in the eye 4 to which the line 5 may be attached in any convenient way. At the base of the projectile a cartridge case 6 is attached, the forward end of which is closed by the cup 7,

and the rear end 8 is preferably formed integral with the cylindrical portion of the cartridge case 6 and is provided with a series of radial grooves 9, which permit the rear end of the cartridge case to be blown out rearwards and outwards when the propelling charge is exploded, as will be hereinafter described.

Passing through the centre of the cartridge case is a stem 10 having its forward end enlarged and screw-threaded, as at 11, to engage in the corresponding screw threads 12 in a socket in the base of the projectile.

The stem 10 is flanged, as at 13, which flange serves to bind the cup of the cartridge case close up against the rear end of the projectile, and thus hold the cartridge case firmly to the projectile. The rear end of this stem 10 is chambered, as at 14, to receive the cap 15 mounted over the anvil 16, which anvil is perforated so as to carry the flame 70 of the cap through the passage 17 and the opening 18 in the stem to the propelling charge 19 contained in the cartridge case.

The outer end of the cartridge case and the various joints are coated with shellac, 80 white lead, or other protective or water proof substances, such as 20 in Figure 2, so that the fixed ammunition may be stored away without danger of material deterioration.

In use, the fixed ammunition is loaded in the gun, and the line may be either previously attached, or attached after the ammunition is in the gun. The base of the cartridge case will project down into the bore and the primer will be fired by any suitable mechanism, such as that shown in our copending application already referred to.

When the propelling charge is ignited, the projectile will be propelled forwards, and as it progresses forward the powder gases will blow out the rear end 8 of the cartridge case, causing the same to serve as a gas check in the bore of the gun, thus sealing the bore against the escape of the powder gases and utilizing a large proportion of the energy of the propelling charge in propelling the projectile.

After the projectile leaves the bore of the gun, the pressure of the air on the line as it is drawn from the reel, not shown, will cause the projectile to tumble or turn with its heavy end forwards, and the eye 4 in the

rear position, which position will be maintained by the resistance of the air on the line as the projectile continues its trajectory.

The projectile may be cast of cheap metal, such as malleable iron, and then finished and painted or covered with protecting material.

The only portion of the projectile which need be finished is its outer wall, which should be turned true and concentric, and then thoroughly lubricated to prevent rusting.

The forward end of the projectile, including the rod 3 and the eye 4, should be well painted to prevent rust.

15 The cartridge case may be drawn of brass or other suitable material, as may also the cup 7 closing the forward end thereof, and the propelling charge may be of ordinary black powder.

20 Thus it will be seen that we provide fixed ammunition for line throwing guns of which the projectile may be made very cheaply, and is not likely to become injured from storage; and in which the cartridge case and 25 its contents may also be made of cheap materials, with easily constructed parts.

It will be obvious that various modifications might be made in the herein described device, and in the construction and operation 30 of the same which could be used without departing from the spirit of our invention, and we do not mean to limit the invention to such details except as particularly pointed out in the claims.

35 Having thus described our invention, what we claim and desire to secure by Letters Patent of the United States is:—

1. Fixed ammunition for use with line throwing guns, comprising a projectile having a cylindrical body portion, and a forwardly projecting stem terminating in an eye, a cartridge case containing the propelling charge closed at both ends and provided with a central rod screwed into the base of

said projectile, and provided with a flange 45 holding said cartridge case attached to said projectile, and a primer carried by said rod and adapted to explode said propelling charge, substantially as described.

2. Fixed ammunition for muzzle loading 50 guns comprising a projectile, a rearwardly extending stem on said projectile, a cartridge case secured to said projectile solely by means of said stem and containing a propelling charge, and a primer for igniting 55 said charge carried at the extremity of said stem.

3. Fixed ammunition for muzzle loading guns comprising a projectile, a rearwardly extending stem threaded into said projectile, 60 a cartridge case having a portion thereof clamped between said projectile and a flange on said stem, a propelling charge in said cartridge case, and a primer for igniting said charge carried by said stem. 65

4. In combination, a projectile, a stem carried by and projecting from the projectile, a cartridge case secured to the projectile by said stem, said cartridge case having a rear portion only weakened sufficiently to cause 70 the exploding charge to blow out rearwardly, a propelling charge in said case, and a primer for said charge, said primer being carried by said stem.

5. Fixed ammunition comprising a projectile and cartridge case secured to the projectile and adapted to leave the piece with the projectile, a stem secured to the projectile and extending rearwardly therefrom, 75 said cartridge case being formed of sheet metal and having a forward end lying along and secured to the rear end of the projectile by said stem and a rear end weakened sufficiently to cause the exploding charge to blow out rearwardly. 80

GREGORY C. DAVISON.
CECIL P. CAULKINS.
